UNITED STATES PATENT OFFICE.

JOHN DOBBIE, OF LEITH, SCOTLAND.

DESIGN FOR A REVERSIBLE CUTTER FOR STONE-DRESSING.

SPECIFICATION forming part of Design No. 29,185, dated August 9, 1898.

Application filed April 23, 1898. Serial No. 678,670. Term of patent 14 years.

To all whom it may concern:

Be it known that I, JOHN DOBBIE, contractor, a subject of the Queen of the United Kingdom of Great Britain and Ireland, residing at 5 Dobbie's Wharf, Old Bridge End, Coal Hill, Leith, Scotland, have invented and produced a new and original Design for Reversible Cutters for Stone-Dressing Tools, of which the following is a specification, reference being had 10 to the accompanying drawing, forming part thereof.

The drawing is a perspective view of a reversible cutter for stone-dressing tools, showing my new design.

15 As shown in the drawing, the leading or material feature of my design consists of the reversible cutter for stone-dressing tools, having the slightly-tapered blades B B and the central angular rib or bead A, running parallel with and situated midway between the cutting edges of the blades B B and projecting from both faces of the cutter. 20

Having thus described my invention, the following is what I claim as new therein and desire to secure by Letters Patent: 25

The design for a reversible cutter for stone-dressing tools, substantially as herein shown and described.

JNO. DOBBIE.
